UNITED STATES PATENT OFFICE.

EDWARD B. ENTWISLE, OF JOHNSTOWN, PENNSYLVANIA, ASSIGNOR TO
THE LORAIN STEEL COMPANY, OF PENNSYLVANIA.

RAILWAY-SWITCH STAND.

SPECIFICATION forming part of Letters Patent No. 666,926, dated January 29, 1901.

Application filed June 15, 1900. Serial No. 20,445. (No model.)

To all whom it may concern:

Be it known that I, EDWARD B. ENTWISLE, of Johnstown, in the county of Cambria and State of Pennsylvania, have invented a new and useful Improvement in Railway-Switch Stands, of which the following is a full, clear, and exact description, reference being had to the accompanying drawings, which form a part of this specification.

10 My invention has relation to certain new and useful improvements in railway-switch stands or ground-switch throws, and is designed to improve that class of switch stands or throws in which the operating-lever is moved in a direction parallel to the track instead of at right angles thereto and also to provide a compact, desirable, and efficient device of this character.

With these objects in view my invention 20 consists in the novel construction and combination of parts, all as hereinafter described, and pointed out in the appended claims, reference being had to the accompanying drawings, forming a part of this specification.

25 In the drawings, Figure 1 is a plan view of my improved switch-stand. Fig. 2 is a section on the line 2 2 of Fig. 1. Fig. 3 is a side view of the base-plate. Fig. 4 is a plan view of the same. Fig. 5 is a detail view of the 30 liner or bushing, and Fig. 6 is a detail view showing the means by which the barrel or cylinder is given longitudinal movement.

The letter A indicates a bottom or base plate designed to be spiked to the wooden track-ties.

35 B is a hollow cylindrical shell, one end portion of which is rotatably seated in a transverse concave bearing A' in the base-plate and secured against displacement by a strap. C, fitting over its upper portion between flanges c thereon and bolted to the base-plate. D is an operating-lever which is secured in an exterior socketed lug b of the said shell.

40 E is a hollow barrel or cylinder which is placed within the shell B and having an angular portion E' projecting beyond the inner end of said shell and engaging an angular opening a in a flange A² of the plate A, whereby said barrel or cylinder is held against rotary movement, but is permitted longitudinal or endwise movement. It is provided with

an exterior helical rib or fin E², which is engaged by a groove in a segmental lug F on the interior of the shell B. On the outer end of the cylinder or barrel E is secured a cap G, 55 which partially fits within the shell B.

H is the switch-rod, which extends through the barrel E and also through the cap G, its outer end being secured by a nut g.

I I' are two cones which are loosely seated 60 on the switch-rod within the barrel E, the cone I seating back against the cap G and the cone I' seating against an interior shoulder i of said barrel and also against a shoulder i' on the said rod. Coiled about the said 65 rod, with its ends seating against these cones, is a helical spring J.

It will be readily seen that when the operating-lever D is moved from the position shown in Fig. 1 through an arc of one hundred and eighty degrees the shell B will be 70 revolved through a corresponding arc, and inasmuch as said shell is fixed against any endwise movement and the barrel E is held against rotary movement, the engagement of 75 the grooved lug F with the helical fin or rod E' will necessarily impart an endwise movement to the said barrel to the left, (looking at Fig. 1,) thereby compressing the spring J, which acts to throw the switch, the compression being effected through the movement of 80 the cone I. Upon the reverse or return movement of the lever D the barrel E is moved to the right, thereby moving the cone I' against the spring and compressing it from the opposite direction to effect the reverse throw of 85 the switch. In assembling the parts the spring J is given some initial compression, and inasmuch as the endwise movement of the barrel E is appreciably greater than the 90 movement required to throw the switch the resulting compression of said spring is not only sufficient to move the switch, but it also assists the initial movements of the lever D. The arrangement of the spring, it will be seen, 95 permits the rod to yield in either direction in case a train should trail through the switch.

L indicates lugs on the base-plate A, over which a loop or hasp on the lever D may be slipped and locked in the usual manner. 100

In order to facilitate assembling the parts and to provide a proper bearing for the shell

B, the concave bearing A' is made deep enough to receive a semicylindrical liner or bushing P, which is slipped in place after the shell and its adjuncts have been assembled on the 5 base-plate. This liner or bushing is of the proper width to fit between the flanges c. It will be readily seen that if the bottom of the bearing A' was itself formed to fit the shell the shell could not be seated, because of the 10 necessity for entering the angular portion E' of the barrel E in the opening a at the same time.

I do not wish to limit myself to the exact construction, arrangement, and combination 15 of parts which I have herein shown and described, as these may be varied in detail without departing from the spirit and scope of my invention.

Having thus described my invention, what 20 I claim, and desire to secure by Letters Patent, is—

1. In a switch stand or throw of the character described, the combination of a base-plate, having a concave bearing therein, the hollow 25 shell seated in said bearing, and formed with circumferential flanges, the liner or bushing seating in said bearing and fitting between said flanges, the strap securing said shell

against longitudinal movement, the barrel seated in said shell, and held against rotary 30 movement, means for rotating said shell, means whereby rotary movement of the shell effects longitudinal movement of said barrel, a switch-rod, and a double-acting spring through which the movements of said barrel 35 are imparted to the switch-rod.

2. In a switch stand or throw of the character described, the combination of the rotary shell, having an interior lug formed with a segmental helical groove, the lever connected 40 to said shell, the barrel within said shell held against rotary movement, but free to move longitudinally, said barrel having a helical rib or fin engaging the said groove, the switch-rod, the double-acting spring seated on said 45 rod within the said barrel, and means whereby longitudinal movement of the said barrel in either direction effects a compression of the said spring and thereby moves the said rod.

In testimony whereof I have affixed my signature in presence of two witnesses.

EDWARD B. ENTWISLE.
